UNITED STATES PATENT OFFICE.

WALDEMAR KOPS, OF NEW YORK, N. Y., ASSIGNOR TO KOPS BROS., OF NEW YORK,
N. Y., A FIRM.

APPAREL GARMENT.

Application filed August 10, 1921. Serial No. 491,108.

To all whom it may concern:

Be it known that I, WALDEMAR Kops, a citizen of the United States, residing in the borough of Manhattan, city, county, and State of New York, have invented an Improvement in Apparel Garments, of which the following is a specification.

This invention relates to an apparel garment and more particularly to an apparel garment which is adapted in use to be worn next to the body. The object of the invention is the provision of a garment made as a unitary structure to serve the combined purposes of a corset, brassière, and an under vest, and may also be so constructed as to include with these garments an underdrawers. The garment made in accordance with the present invention is particularly adapted for use by young or athletic women.

In carrying out the invention the garment made in accordance therewith is preferably constructed of a material having sufficient elasticity to cause the garment to cling and conform to the body to permit of all conceivable movements thereof, and the front portion of the garment is preferably so constructed as to be less yielding than the other portions thereof in order to lend support to the underlying portions of the body of the wearer, this front section being formed by overlapping members or a reinforcing member or otherwise. The upper central portion of the front section is also preferably divided and provided with means for securing the divided portions to one another in order to enable the user to get into and out of the garment more readily than if such a provision were not made. The garment may also be provided with detachable hose supporters which may thus be removed therefrom in order not to injure the hose supporters or the elastic fabric of which the same are composed in laundering the garment.

In the drawing:

Fig. 1 is a perspective view illustrating the use of one form of my invention.

Fig. 2 is an enlarged front elevation of the form of garment shown in Fig. 1.

Fig. 3 is a perspective view illustrating the use of another form of the garment made in accordance with my invention.

Fig. 4 is a front elevation on an enlarged scale of the garment shown in Fig. 3, and

Fig. 5 is a section on line 5—5, Fig. 2.

Referring to the drawing and particularly to Figs. 1 and 2, the garment, as will be seen, preferably comprises front members indicated at 10 and 11 respectively, together with back members 12 and 13. The back members 12 and 13 are connected along the line 14 by a suitable seam or line of stitching, while the front member 10 and the back member 12 are connected at the side of the garment along a suitable seam 15, and similarly the front member 11 and the back member 13 are secured to each other along the side of the garment by a suitable seam or line of stitching 16. The front member 11 is provided with an extension 17, and the front member 10 with a similar extension 18. The extension 17 is connected to the front member 11 by a seam or line of stitching 19, and similarly the extension 18 is connected to the front member 10 along a seam 75 or line of stitching 20. The extension 17 at its upper end terminates in the shoulder strap 21 which is connected to a shoulder strap 22 extending from the back member 13 as indicated at 23. In the same manner 80 the front extension 18 terminates at its upper end in a shoulder strap 24 which is connected to a shoulder strap 25 extending from the back member 12 as indicated at 26.

A portion of the front extension 18 overlaps a portion of the front extension 17, and the edge of the front extension 18 is connected to the front member 11 and the extension 17 along the same seam or line stitching that connects the front member 11 and its extension 17, this connection extending from the lower edge of the garment upwardly to a point indicated at 27 from which to the top of the garment the front extension 18 is free. 90 Similarly the edge of the front extension 17 is connected to the front member 10 and the extension 18 in the same seam or line of stitching 20 that connects the front member 10 and its extension 18, this connection extending from the lower edge of the garment upwardly to a point indicated at 28 which corresponds in position to the point 27 so that the upper portion of the front extension 17 above the point 28 is free from other parts of the garment. It will therefore be understood that there are overlying parts in the front of the garment extending from the lower edge thereof to the points 27 and 28, the outer part of this section forming a por- 100 105 110

tion of the extension 18 and the inner part forming the corresponding portion of the extension 17. The lower edges of these overlying portions, as clearly indicated in Fig. 2 are indicated at 29 and 30 respectively, 29 being the lower edge of the extension 17 which conforms to the lower edge of the other parts of the garment, while the lower edge 30 of the extension 18 is preferably spaced appreciably from the edge 29. The lower edge of the front extension 18 may have secured thereto hose supporter straps 31, and similarly at the sides of the garment I may employ hose supporter straps 32 and 33. Furthermore as illustrated in Fig. 2 the upper edges of the front extensions 17 and 18 may be provided with a cord or lace 34 passed through eyelets provided therefor in order to draw these parts of the garment to position after the same has been placed on the body of the wearer. In this garment, as will now be understood, all the parts being made of the same fabric will cling to the body of the wearer and conform thereto and permit movements thereof to the same extent, with the exception of the central front section which is composed of the overlying portions of the fabric in which there will not be the same elasticity as in other parts of the garment so that this front central section tends to lend a support to the underlying parts of the body of the wearer. The garment thus constructed, as will be understood, performs the function of a brassière, a corset and an under vest.

By reference to Figs. 3 and 4 of the drawing, it will be seen that the construction of the front members 37 and 38 is similar to that in the other form of the invention, with the exception of the manner in which they are formed at the top thereof. In this form of the garment the front sections 37 and 38 are connected to a front central section 40 along the seams or lines of stitching indicated at 39, this central section 40 extending from the lower edge to the upper edge of the garment and in the upper portion thereof being divided as indicated at 41 and fitted with a binding or reinforcement 42 having eyelets therein to receive laces 44 by which the upper portion of the garment is adjusted to position on the wearer. The front central section of the garment also includes an inner reinforcing member 45 which extends from approximately the line 46 to the lower edge of the garment and is connected in the same seams or lines of stitching 39 by which the front members are connected to the outer front section 40. This obviously has the same effect as the overlying front extensions as illustrated in the first form of the invention and tends to make this portion of the garment less elastic than the other portions

thereof thereby lending a support to the underlying parts of the body of the wearer. In this form of the garment the back sections are indicated at 47 and 48 and are connected by shoulder straps 49 and 50 to the front portions of the garment as clearly shown in Fig. 4 or in any other suitable manner. Furthermore in this form of the invention the lower portions thereof may be provided with tapes 51 secured at one end to the garment and provided at the other with a button hole to be looped and connected to a button 52 or otherwise secured in place for cooperating with a buckle 53 attached to the usual hose supporter strap.

In the use of all the forms of the invention the garment performs the functions, as hereinbefore stated, of a corset, a brassière and under vest, and in all forms of the invention the front central section of the garment is so constructed as to be materially less yielding than the other portions of the garment to form a support for the underlying parts of the body of the wearer, particularly when in a standing position when the tension is applied to the front hose supporters and thus transmitted to this front central section of the garment.

I claim as my invention:

1. An apparel garment forming a combined undervest, corset and brassière and comprising a single piece body member adapted to cover the body of the wearer from substantially the busts to the thighs and made of a material sufficiently elastic to cling and conform to the body of the wearer, the said body member having longitudinal overlapping extensions in the front thereof to form a multi-ply front supporting section which is less yielding than the other sections of the garment, the longitudinal edge of the extension from one side of the body member being connected to the other side of the body member and the longitudinal edge of the extension from the said other side of the body member being connected to the first aforesaid side of the body member of the garment.

2. An apparel garment forming a combined undervest, corset and brassière and adapted to completely surround the body of the wearer from substantially the busts to the thighs and comprising a circumferentially continuous body member, extensions secured to the front edges of the body member, the said extensions overlapping each other to form a multi-ply front supporting section which is less yielding than the other sections of the garment, the outer edge of the outer ply of the multi-ply section being connected to the adjacent front edge of the body of the garment and the inner edge of the inner ply of the multi-ply front section of the garment being connected to the front

edge of the other side of the body of the garment.

3. An apparel garment forming a combined undervest, corset and brassière and comprising a single piece body member adapted to cover the body of the wearer from substantially the busts to the thighs and made of a material sufficiently elastic to cling and conform to the body of the wearer, 10 the said body member having overlapping front portions, the edges of which are connected continuously to the body member to form a multi-ply front supporting section which is less yielding than the other sections 15 of the garment, means for adjustably connecting the upper ends of the front section to each other, and hose supporters connected to and depending from the lower edge of the multi-ply front supporting section of the garment. 20

4. An apparel garment forming a combined undervest, corset and brassière and adapted to completely surround the body of the wearer from substantially the busts 25 to the thighs comprising a circumferentially continuous body member, extensions secured to the front edges of the body member, the said extensions overlapping each other to form a multi-ply front supporting section 30 which is less yielding than the other sections of the garment, the outer edge of the outermost ply of the multi-ply section being continuously connected to the adjacent front edge of the body of the garment and the 35 inner edge of the innermost ply of the multi-ply front section of the garment being continuously connected to the front edge of the other side of the body of the garment.

5. An apparel garment forming a combined undervest, corset and brassière and adapted to completely surround the body of the wearer from substantially the busts to the thighs comprising a circumferentially continuous body member, extensions secured 40 to the front edges of the body member, the said extensions overlapping each other to form a multi-ply front supporting section which is less yielding than the other sections of the garment, the outer edge of the outermost ply of the multi-ply section being continuously connected to the adjacent front edge of the body of the garment and the 45 inner edge of the innermost ply of the multi-ply front section of the garment being continuously connected to the front edge of the other side of the body of the garment, means for adjustably connecting the upper portions 50 of the multi-ply front supporting section, and hose supporters depending from the lower edge of the multi-ply front supporting section of the garment. 60

6. An apparel garment forming a combined undervest, corset and brassière adapted to completely cover the body of the wearer 65 from the bust to the thighs comprising a cir-

cumferentially continuous body member made of material sufficiently elastic to cling and conform to the body of the wearer, and extensions forming a multi-ply front supporting section in the garment which is less 70 yielding than the other sections of the garment, the outer member of the multi-ply front section being connected along one edge to the front edge of one front portion of the body of the garment and being connected 75 along its entire opposite edge to the other front edge of the body of the garment, the inner member of the multi-ply front supporting section of the garment being connected along one edge continuously to the 80 front edge of the last aforesaid front section of the garment and entirely along its opposite edge to the front edge of the first aforesaid front section of the garment, the upper 85 portions of the inner and outer members of the multi-ply front supporting section being free from each other and from the body portions of the garment for a predetermined extent along oppositely disposed edges, and means for connecting the upper portions of 90 the multi-ply front sections of the garment. 95

7. An apparel garment forming a combined undervest, corset and brassière adapted to completely cover the body of the wearer from the bust to the thighs comprising a circumferentially continuous body member made of material sufficiently elastic to cling and conform to the body of the wearer, extensions forming a multi-ply front supporting section in the garment which is less yielding than the other sections of the garment, the outer member of the multi-ply front section being connected along one edge to the front edge of one front portion of the body of the garment and being connected 105 along its entire opposite edge to the other front edge of the body of the garment, the inner member of the multi-ply front supporting section of the garment being connected along one edge continuously to the 110 front edge of the last aforesaid front section of the garment and entirely along its opposite edge to the front edge of the first aforesaid front section of the garment, the upper 115 portions of the inner and outer members of the multi-ply front supporting section being free from each other and from the body portions of the garment for a predetermined extent along oppositely disposed edges, a lacing device for adjustably connecting the 120 upper portions of the multi-ply front section of the garment, and hose supporters connected to and depending from the lower edge of the multi-ply front section of the garment. 125

8. An apparel garment comprising front and back sections suitably connected and made of material of sufficient elasticity to cause the same to cling and conform to the body, an extension connected along one edge 130

- to the edge of one front member and along a part only of its opposite edge to the other front member, an extension connected along one edge to the last aforesaid front member 5 overlying the aforesaid extension and connected along a portion only of its opposite edge to the edge of the first aforesaid front member whereby the upper portions of the extensions are disconnected, and means for 10 connecting the said upper ends of the said extensions, the said extensions forming a front central longitudinal section which is relatively less yielding than the other parts of the garment.
- 15 9. An apparel garment comprising front and back sections suitably connected and made of material of sufficient elasticity to cause the same to cling and conform to the body, an extension connected along one edge 20 to the edge of one front member and along a part only of its opposite edge to the other front member, an extension connected along one edge to the last aforesaid front member
- overlying the aforesaid extension and connected along a portion only of its opposite edge to the downward edge of the first aforesaid front member whereby the upper portions of the extensions are disconnected, means for connecting the said upper ends of the said extensions, the said extensions forming a front central longitudinal section which is relatively less yielding than the other parts of the garment, and tension devices connected to and extending downwardly from the overlying extension of the front central longitudinal section for applying downward tension thereto by which and because of being relatively less yielding than the other parts of the garment the said front central longitudinal section tends to support 40 the underlying parts of the body of the wearer.

Signed by me this 5th day of August, 1921.

WALDEMAR KOPS.
